(57) **CLAIM**

The ornamental design for a faucet, as shown and described.

DESCRIPTION

FIG. 1.1 is a perspective view of the faucet which is the subject of our new design;

FIG. 1.2 is a left side elevational view thereof;

FIG. 1.3 is a right side elevational view thereof;

FIG. 1.4 is a front elevational view thereof;

FIG. 1.5 is a rear elevational view thereof;

FIG. 1.6 is a top plan view thereof;

FIG. 1.7 is a bottom plan view thereof;

FIG. 1.8 is a perspective view of the faucet in a retracted position;

FIG. 2.1 is a perspective view of a faucet joint;

FIG. 2.2 is a right side elevational view thereof;

FIG. 2.3 is a left side elevational view thereof;

FIG. 2.4 is a front elevational view thereof;

FIG. 2.5 is a rear elevational view thereof;

FIG. 2.6 is a top plan view thereof; and,

FIG. 2.7 is a bottom plan view thereof.

The dotted line portions are by way of example only and form no part of the claimed design.
